US0D1051507S

(12) **United States Design Patent** (10) **Patent No.:** **US D1,051,507 S**
(45) **Date of Patent:** **** Nov. 12, 2024**

(54) **FIRE EXTINGUISHER**

(71) Applicant: **Yiming Zhang**, Shenzhen (CN)

(72) Inventor: **Yiming Zhang**, Shenzhen (CN)

(73) Assignee: **X-SENSE USA LLC**, Wilmington, DE (US)

(**) Term: **15 Years**

(21) Appl. No.: **29/930,775**

(22) Filed: **Mar. 1, 2024**

(51) **LOC (14) Cl.** **29-01**

(52) **U.S. Cl.**

USPC **D29/125**

(58) **Field of Classification Search**

(57) **CLAIM**

The ornamental design for a fire extinguisher, as shown and described.

DESCRIPTION

FIG. 1 is a front top right side perspective view for a fire extinguisher, showing my new design;

FIG. 2 is a rear bottom left side perspective view of FIG. 1 thereof;

FIG. 3 is a front elevational view of FIG. 1 thereof;

FIG. 4 is a rear elevational view of FIG. 1 thereof;

FIG. 5 is a left side elevational view of FIG. 1 thereof, the right side elevational view being a mirror image.

FIG. 6 is a top plan view of FIG. 1 thereof; and,

FIG. 7 is a bottom plan view of FIG. 1 thereof.

The broken lines indicate unclaimed portions of the fire extinguisher and form no part of the claimed design.

1 Claim, 7 Drawing Sheets
